UNITED STATES PATENT OFFICE.

NEWTON J. LINDESMITH, OF WYNNEWOOD, OKLAHOMA.

PLOW.

No. 927,363.

Specification of Letters Patent.

Patented July 6, 1909.

Application filed July 13, 1908. Serial No. 443,218.

To all whom it may concern:

Be it known that I, NEWTON J. LINDESMITH, a citizen of the United States, residing at Wynnewood, in the county of Garvin, State of Oklahoma, have invented certain new and useful Improvements in Plows; and I do hereby declare the following to be a full, clear, and exact description of the invention, such as will enable others skilled in the art to which it appertains to make and use the same.

This invention relates to improvements in plows, and has for one of its objects to improve the construction and increase the efficiency and utility of devices of this character.

Another object of the invention is to provide a simply constructed attachment for plows whereby the friction incident to the movement through the ground is reduced and the "draft" thereby materially improved.

With these and other objects the invention consists in a beam having a lateral offset at the point with a mold board overhanging the offset, and a disk mounted for rotation rearwardly of the offset and with its outer side face convex and flush with the landside face of the offset and the landside edge of the mold board.

The invention further consists in a beam having a lateral offset at the point with a mold board overhanging the offset and a frame extending rearwardly of the mold board and beam, the frame carrying a bearing supporting a journal having a disk operating with its outer side face flush with the landside face of the offset and the landside edge of the mold board.

The invention further consists in certain novel features of construction as hereafter shown and described and then specifically pointed out in the claims, and in the drawings illustrating the preferred embodiment of the invention, Figure 1 is a side elevation of a plow from the "land" side, with the improvements embodied therein. Fig. 2 is a plan view in section on the line 2-2 of Fig. 1. Fig. 3 is a section on the line 3-3 of Fig. 2. Fig. 4 is a section on the line 4-4 of Fig. 2, with the mold board detached. Fig. 5 is a perspective view of the frame detached.

The improved device comprises a plow beam 10 having a lateral offset 11 at its point with the outer face of the offset form-

ing a portion of the "landside" of the plow. The mold board 12 is of the usual form and attached to the beam in the usual manner by bolts 13 and with its landside edge 14 in alignment with the outer or landside face of the offset.

Extending rearwardly of the beam 10 is a frame comprising spaced sides 15-16 and a rear portion 17, with a lateral web 18 at the forward end of the side 15 to form means for riveting or bolting the frame to the beam.

Formed integral with the frame members 15-16 is a half bearing 19 with the inner end of the half bearing formed oblique to bear against the inner face of the mold board 12 and secured thereto by a bolt 20.

Disposed upon the half bearing 19 is a bearing cap 21 and secured thereto by bolts 22, or other suitable fastening devices, the cap overhanging the lower bearing member. Fitting rotatively within the bearing members is a journal 23 having an enlarged inner end 24 fitting in corresponding cavities in the bearing members, so that while the journal is free to rotate in the bearing it is held from longitudinal movement therein. The journal is also provided with a shoulder 26 near its outer end and beneath the overhang 25 of the cap, and serving as a sand guard to the journal, while the overhang also serves as a guard or shield to the journal.

Secured upon the outer end of the journal 23 is a disk 25 having its outer face slightly convex and in substantial alignment with the landside edge 14 of the mold board, and the landside face of the offset 11, the lower edge of the disk coming about flush with the lower line of the offset. The disk thus replaces the ordinary landside of the plow and provides a simply constructed and easily applied rolling landside, whereby the friction is materially decreased and the draft correspondingly improved.

The improved device may be applied to any of the various forms of plows and listers by making slight and immaterial changes in the construction, as will be obvious.

A suitable dust proof oil cup 27 is attached to the cap member 21, preferably above the enlarged inner end 24 of the stub axle 23, to supply the requisite lubrication.

What is claimed, is:

1. In a plow, the combination of a beam having a lateral offset at its point, a mold board overhanging the offset, a frame ex-

tending rearwardly of the mold board and beam and having a half bearing, means for connecting said frame and its half bearing to the mold board, a journal mounted for 5 rotation in said half bearing, a cap engaging over said journal and secured to said half bearing, and a disk carried by said journal and operating with its outer face flush with the landside face of the offset and the landside 10 side edge of the mold board.

2. In a plow, the combination of a beam having a lateral offset at its point, a mold board overhanging the offset, a frame extending rearwardly of the mold board and beam, a half bearing carried by said frame and with a half socket at its inner end, means 15 for connecting said frame to the beam, and to the mold board, a journal mounted for

rotation in said half bearing and having a collar at the inner end and a collar intermediate the ends, with the end collar engaging in the half socket and the intermediate collar bearing against the half bearing, a disk carried by said journal and operating with its outer face flush with the landside 20 face of the offset and the landside edge of the mold board, and a cap engaging over said half bearing and provided with sockets bearing over the collars of the journal.

In testimony whereof, I affix my signature, in presence of two witnesses.

NEWTON J. LINDESMITH.
